CLAIM

The ornamental design for a display screen with graphical user interface as shown and described.

DESCRIPTION

The FIGURE is a front view of a display screen with graphical user interface showing our new design. The exterior even-length broken lines illustrate the boundary of the claimed design and portions of a display screen and form no part of the claimed design. The remaining even-length broken lines illustrate portions of the graphical user

substrate portion (Continued)

interface and form no part of the claimed design. The broken line text forms no part of the claimed design.
